UNITED STATES PATENT OFFICE

ALBERT H. ACKERMAN, OF SOUTH BEND, INDIANA, ASSIGNOR TO THE STUDEBAKER CORPORATION, OF SOUTH BEND, INDIANA, A CORPORATION OF NEW JERSEY

UPHOLSTERY UNIT

Application filed May 17, 1929. Serial No. 363,763.

This invention relates to vehicle doors and particularly to an upholstery unit therefor.

The principal object of the invention is to provide a new and novel means for securing the free ends of a finishing tape to an upholstery panel whereby the mitered ends of said tape present a smooth and even joint.

The further object is to provide an upholstery panel frame having an opening 10 therein with a closure panel for the opening, and a novel means for attaching a finishing tape or the like to the closure panel.

A further object is to provide a filler panel with a slot therein through which the 15 free ends of the finishing tape or the like may be inserted so that the ends of the tape are unexposed and to provide an even and neat finish for the finishing tape.

A further object is to provide means 20 whereby the free ends of the finishing tape can be inserted through an upholstery panel and secured to the rear face of the panel.

A further object is to provide an upholstery panel with a suitable covering there- 25 for, and a finishing tape or the like positioned over the covering, the free ends of the tape being secured on the opposite side of the panel so that the mitered edges of the finishing tape present an even and true line 30 in the exposed face thereof.

The above and other objects relating to certain details of construction and methods of manufacture to be hereinafter described with reference to the accompanying draw- 35 ing, and then claimed, will be apparent from the detailed description to follow.

In the accompanying drawing which shows a suitable embodiment of the present invention,

40 Figure 1 is a side elevation of the upholstery panel for a vehicle door, showing my invention included therein.

Figure 2 is an enlarged detailed sectional view taken on the line 2—2 of Figure 1.

45 Figure 3 is an enlarged fragmentary sectional view taken on the line 3—3 of Figure 1.

Figure 4 is an enlarged fragmentary ele- 50 vation showing a portion of the upholstery

panel, certain parts being broken away to more clearly illustrate the invention.

Figure 5 is a rear view of a portion of the panel showing the means for securing the free ends of the finishing tape to the 55 panel.

Figure 6 is a fragmentary view showing the slots in the panel through which the ends of the finishing tape may be inserted.

In the drawing in which like numerals 60 refer to like parts throughout the several views, I have shown an upholstery panel frame 1 having an opening 2 therein which as illustrated in the drawings may be of considerable size. The panel frame 1 which is 65 preferably formed from cardboard, fibre board or the like may if desired be of other material such as laminated wood, sheet metal, paper or other material and is preferably covered on its outer face with suitable material such as mohair, velour broadcloth or the like as indicated at 3.

The opening 2 formed in the panel frame 1 is closed with a second panel 4 preferably 70 secured to the rear face thereof which may 75 be of the same material as the panel 1, the panel 4 preferably being covered with a suitable upholstery material 5 which may or may not be of the same texture and color as the material 3 on the panel frame 1, de- 80 pending upon the design and color scheme carried out in the upholstery of the vehicle body. If desired, the central portion of the panel 4 may have padding material 6 there- 85 on to bring the central portion thereof sub- stantially flush with or extending outwardly from the material 3 on the panel frame 1, but preferably the padding 6 does not ex- 90 tend over the full surface of the panel 4 in order that there may be a depressed por- 95 tion extending within the edges of the open- 95 ing 2 to receive a finishing tape, broadlace or the like 7, as is clearly shown in Figure 2. The filled panel 4 is preferably somewhat larger than the opening 2 formed in the pan- el 1 and after the upholstery 5 has been applied to the panel 4 the same is secured to the rear face of the panel 1 as by stitching the same as at 8 thereto as is shown in Fig- 100 ures 4 and 5.

The finishing tape 7 is preferably stitched along its edges at 9 to the upholstery 5 and the panel 4 to properly secure the same thereto. As the tape 7 is used as a finishing member to add decorative beauty to the panel it is necessary that the same be applied so that the same lays smooth and true and the edges do not bulge or form uneven seams or joints. Particularly at the mitered corners of the tape it is necessary that the same lie true and smooth and to accomplish the desired result I provide openings or slots 10 extending through the upholstery 5 and the panel 4 through which the free ends of the tape 7 are inserted. The free ends 11 of the tape 7 are folded on the rear face of the panel 4 and are held in taut and smooth position thereon by means of the adhesive 12. The adhesive 12 which may be gummed tape or the like preferably extends beyond the free ends 11 so that they are substantially covered by the adhesive which prevents raveling and fraying of the same and holds the tape 7 from pulling loose and working up through the slots 10.

Heretofore it has been the practice to sew the mitered edges of a finishing tape to its support and in so doing it was necessary to turn under the raw edges before the tape was sewed which resulted in a bulge or projecting portion of the tape at the point where a true, even and smooth seam was desired.

By extending the free ends of the tape through the slots and securing the same to the back of the supporting panel in the manner above described, the mitered edges of the finishing tape present a true and even seam and greatly adds to the beauty of the completed upholstered unit.

The upholstery 3 covering the panel 1 preferably has its free edges folded over the edges of the panel 1 and is secured to the under surface thereof. As the panel 4 is considerably larger than the opening 2 formed in the panel 1 the upholstery 5 therefor can be of the same size and contour as its supporting panel and have its edges trimmed even therewith. However, if it is so desired the free edges of the upholstery 5 can be folded over the panel 4 in the same manner as the upholstery 3 is folded over the edges of the panel 1.

Having shown and described the preferred embodiment of my invention, it will be understood that formal changes and details relating to manufacture and positioning of parts may be resorted to without departing from the spirit and scope of my invention, the scope of which is commensurate with the appended claims.

What I claim is:

1. An upholstery unit comprising, an upholstery panel frame having an opening

therein, a closure panel having a slot formed therein secured to said panel frame for closing said opening, a finishing tape secured to the outer face of said closure panel having a free end extending through said slot, and an adhesive tape for securing said free end of said tape to the back of said closure panel. 70

2. An upholstery unit comprising, an upholstery panel frame having an opening 75 therein, a covering for the outer face of said panel frame, a closure panel having spaced slots formed therein secured to the rear face of said panel frame for closing said opening, a finishing tape secured to the outer face of said closure panel having its free ends extending through said slots, and adhesive tape secured over the free ends of said tape and to the back of said closure panel for securing said free ends to the back 85 of said closure panel.

3. An upholstery unit comprising, an upholstery panel frame having an opening therein, a covering for said panel frame, a closure panel having slots formed therein 90 for closing said opening, a covering for said closure panel having slots therein aligned with said first named slots, means for securing said closure panel to said panel frame, a finishing tape sewed along its side edges 95 on the outer face of said covering for said closure panel, said tape having its free ends extending through said slots, and adhesive tape for securing the free ends of said tape to the back of said closure panel. 100

4. An upholstery unit comprising, an upholstery panel having slots formed therein, a covering for said panel having slots aligned with said slots in said panel, a finishing tape secured on said covering having 105 its free ends extending through said slots, and means for securing the free ends of said tape to the back of said closure panel.

5. An upholstery unit comprising, an upholstery panel having slots formed therein, 110 a covering for said upholstery panel having slots aligned with said slots in said panel, a finishing tape sewed along its side edges to said covering and having its free ends extending through said slots, and means for securing the free ends of said tape to the back of said closure panel. 115

6. An upholstery unit comprising, an upholstery panel having slots formed therein, 120 a covering on the outer face of said panel having slots aligned with said slots in said panel, a finishing tape sewed along its free edges to said covering and having its free ends extending through said slot, and adhesive tape secured to the free ends of said tape and to the back of said closure panel for securing said free ends to the back of said closure panel. 125

7. An upholstery unit comprising, an upholstery panel having slots formed therein, 130

a covering for said panel having slots aligned with the slots in said panel secured to the outer face thereof, a plurality of pieces of finishing tape secured adjacent to the side edges thereof to said covering and having the free ends thereof extending through said slots, said tape being positioned on said covering so that the mitered ends thereof form even joints, and a plurality of pieces of adhesive tape for securing the free ends of said finishing tape to the back of said closure panel.

Signed by me at South Bend, Indiana,
this 15th day of May, 1929.

15 ALBERT H. ACKERMAN.
